UNITED STATES PATENT OFFICE.

FLOYD W. CHENOWETH, OF PERRY, IOWA.

RING EXPANDER.

Application filed March 10, 1921, Serial No. 451,282. Renewed February 27, 1925.

To all whom it may concern:

Be it known that I, FLOYD W. CHENOWETH, a citizen of the United States of America, and resident of Perry, Dallas County, Iowa, have invented a new and useful Ring Expander, of which the following is a specification.

The object of this invention is to provide an improved construction for a ratchet-operated multiple-screw device for expanding open rings such as wheel rims, boiler sheets and the like.

A further object of this invention is to provide an improved ratchet-lever operating mechanism for a ring expander.

With these and other objects in view, my invention consists in the construction, arrangement and combination of elements hereinafter set forth, pointed out in my claims and illustrated by the accompanying drawing, in which—

Figure 1 is a plan of my improved ring expanding device, a portion of the operating lever being broken away to economize space. Figure 2 is a side elevation on a reduced scale, showing the device mounted on a supporting stand. Figure 3 is a longitudinal section of the operating lever, on an enlarged scale. Figure 4 is a cross-section on the line 4—4 of Figure 3.

In the construction of the device as shown the numerals 10, 11 designate spaced parallel sills which may be of any suitable dimensions. Mounted transversely on and supported in spaced parallel relation by the sills 10, 11 are bars 12, 13; the bar 12 being fixed near its ends to the sills 10, 11 as by welding, and the bar 13 being slidable on the upper margins of said sills. Pressure screws 14, 15 are arranged in alignment and are threaded through central portions of the bars 12, 13 respectively. An adjusting and pressure member 16 is arranged parallel with the pressure screws 14, 15 and has its end portions oppositely threaded and extending loosely through smooth holes in the bars 12 and 13; and an adjusting, operating and pressure member 17 of similar form is mounted loosely through the opposite end portions of said bars, adjacent the sill 11. The ends of the bars 12, 13 and the outer ends of the screws 14, 15, furnish six spaced points for contacting and applying outward pressure at times to a ring such as 18 which may be mounted in the plane of the bars 12,

13 and screw devices, and may be supported by end portions of the sills 10, 11 as shown in Figure 1.

Blocks 19, 20 are threaded on opposite end portions of the member 16 and means is provided for holding said blocks against rotation when the member 16 is turned on its axis. In this instance the inner faces of the bars 12, 13 are formed with V-shaped notches, and the blocks 19, 20 are formed with V-shaped lugs 24 on their outer faces entering said notches. Similar blocks 21, 22 are threaded on opposite end portions of the screw member 17. A retractile coil spring 23 is fixed at its ends to central portions of the bars 12, 13 and tends to hold the bar 13 toward the rigid or fixed bar 12, and also to cause the V-shaped lugs 24 to enter the notches of said bars. When so engaged the blocks 19, 20, 21, 22 are held against turning and the screw members 16, 17 are caused to travel with respect to the bars 12, 13 when rotated on their axes. The threading of the members 16, 17 through the blocks 19, 20, 21, 22 and the engagement of the lugs 24 of the blocks with the notches in the bars 12, 13 constitutes a screw connection between said members 16, 17 and the bars, by which the bars have a freedom of movement relative to the screw members.

Operating devices A, B are provided for rotating the respective screw members 16, 17 manually, and said devices are alike in construction, except that the lever of the member 17 preferably is considerably longer than that of the member 16. The operating device B is shown in detail in Figures 3 and 4 and will now be described.

Formed on or fixed to the central portion of the screw member 17 is a ratchet hub or boss 25 formed with peripheral ratchet teeth and notches preferably square in cross-section. A sleeve 26 is fitted to the ratchet boss 25 and is adapted for rotative movement thereon; and a tubular lever 27 is formed on or fixed to said sleeve and communicates therewith at one end. A plunger 28 is mounted in the tubular lever 26 and has its outer end projecting therefrom and provided with a head 29, while the inner end of said plunger projects within the sleeve 26 and is provided with a ratchet dog 30 adapted to engage the teeth of the boss 25 and rotate said boss and the member 17 in one direction. The plunger and ratchet dog 30 are reversible so that

the boss and member 17 may be selectively rotated in either direction as desired. A cap 31 is provided for the outer end of the tubular lever 27 and is provided with a hole 5 through which the plunger 28 extends loosely. An expansive spring 32 is coiled around a portion of the plunger 28 and impinges at one end the inner face of the cap 31 and at its other end a collar 33 fixed to 10 said plunger, whereby the dog 30 is yieldingly pressed to engagement with the teeth of the boss 25. The cap 31 is also formed with a transverse slot 34 adapted to receive a pin 35 mounted through the plunger 28, 15 which controls the relative position of the ratchet dog 30 as to selective operation of the boss and member 17 in opposite directions. When it is desired to reverse the direction of rotation the plunger is withdrawn 20 partially from the tubular lever 27 by outward pull on the head 29 against the spring 32, thus releasing the dog 30 from engagement with the ratchet teeth of the boss 25 and the pin 35 from the slot 34. Then the 25 plunger is turned through an arc of one hundred and eighty degrees and allowed to move inwardly of the tubular lever under pressure of the spring 32, the ratchet dog 30 thus being reversed and being in position to 30 operate the toothed boss and member 17 in the opposite direction.

In practical operation the device is mounted within an open ring, such as 18, which is to be expanded. In the case of a narrow 35 ring, such as a detachable wheel rim, one of the devices is employed, and may conveniently be mounted on a supporting stand, such as 36, as shown in Figure 2, and be arranged thereon in horizontal position. In 40 the case of a wide ring, such as a boiler sheet, two of the devices may be employed, one at each end of the sheet, and may be placed therein in vertical planes or in any other convenient position. In either case the device is so arranged that the operating device B, having the longer lever, is adjacent to and may be operated through the opening in the ring, as indicated in Figure 1. The screws 45 14, 15 are adjusted manually in the bars 12, 13, by rotation, until their outer ends are in contact, at diametrically opposite points, with the inner face of the ring. The members 16, 17 are also adjusted, by operation of the adjusting devices A and B, until the 50 ends of the bars 12, 13 are in substantial contact with the inner face of the ring, the bar 13 in such operation sliding on the sills 10, 11. Then pressure is applied by operation of the devices A and B, conjunctively or 55 alternately, the tubular levers 27 of such devices being oscillated through convenient arcs to cause the ratchet dogs 30 to engage and rotate the toothed bosses 25, and through 60 them the members 16 and 17.

65 The longer handle of the operating device

B is possible because of the suggested arrangement whereby it may project through the opening of the ring; and is desirable in that it provides greater lever advantage at the point of greatest tension and resistance 70 of the ring as expansion takes place.

I do not desire to be understood as limiting myself to the precise construction set forth, as modifications may be employed without departing from the spirit of my invention. 75

I claim as my invention—

1. A ring-expanding device of the class described, comprising a support, a bar fixed to said support, a bar parallel with the first 80 bar and slidable on the support, separate pressure devices adjustably mounted at central portions of the respective bars, pressure devices mounted loosely through both of said bars adjacent the respective ends thereof, 85 said last-named pressure devices having opposite screw connections with the respective bars, and lever means for rotating the last-named pressure devices.

2. A ring-expanding device of the class 90 described, comprising a pair of bars arranged substantially parallel and relatively movable laterally, separate pressure devices adjustably carried by central portions of the respective bars, pressure rods mounted on opposite sides of said pressure devices and each extending loosely through and having opposite screw connections with each of said bars, and means for selectively operating 95 said pressure rods in either direction.

3. A ring-expanding device, comprising a pair of bars arranged substantially parallel and relatively movable laterally, separate pressure devices adjustably carried by said bars, a pressure rod arranged transversely of 105 said bars and having a freedom of movement at opposite sides of its center relative thereto, and having screw connections acting on said bars, and means for operating said pressure rod in either direction, whereby 110 said bars are simultaneously caused to advance or recede relative to said center when said rod is rotated.

4. A ring-expanding device, comprising a 115 pair of bars arranged substantially parallel and relatively movable laterally, separate pressure devices adjustably carried by said bars, a spring device tending to draw said bars together, a pressure rod arranged transversely of and slidable relative to said bars, said rod being oppositely threaded 120 at its ends, members threaded on opposite end portions of said rod and engaging the respective bars, and means for rotating said rod in opposite directions.

Signed at Des Moines, in the county of Polk and State of Iowa, this 27th day of December, 1920.

FLOYD W. CHENOWETH.
